UNITED STATES PATENT OFFICE.

JABEZ COOPER, OF CARNEGIE, PENNSYLVANIA, ASSIGNOR OF ONE-THIRD TO JABEZ COOPER, JR., AND ONE-THIRD TO GEORGE E. PITZER, OF CARNEGIE, PENNSYLVANIA.

PIPE-WRENCH.

No. 893,903.

Specification of Letters Patent.

Patented July 21, 1908.

Application filed November 22, 1907. Serial No. 403,302.

To all whom it may concern:

Be it known that I, JABEZ COOPER, a citizen of the United States, residing at Carnegie, in the county of Allegheny and State of Pennsylvania, have invented certain new and useful Improvements in Pipe-Wrenches, of which the following is a specification, reference being had therein to the accompanying drawing.

10 My invention refers to an improved construction in pipe wrenches and has for its object to provide a simple, strong and economical device for the purpose, having a considerable range of adjustment for various sizes 15 for which purpose one of the pivotally mounted elements of the device is capable of being set forwardly or backwardly by screw engagement with a trunnioned bearing nut pivotally mounted in the other clamping element, and is constructed and adapted to operate in the manner more fully hereinafter described.

In the drawings:—Figure 1 represents a view of the device in side elevation. Fig. 2 25 is a plan view partly broken away. Fig. 3 is a transverse sectional view on the line III, III, of Fig. 1. Fig. 4 is a similar sectional view showing a modified construction of the pivotal mounting.

30 The device comprises two main elements, each of which is provided with a gripping terminal jaw and an operating handle at the other end, one of the elements being divided to provide opposite sides within which is pivotally mounted a nut through which passes the threaded stem of the other element. This construction is illustrated in the drawing, wherein 2 represents the shank or handle of one of said elements, having divided oppositely located sides 3, 3, preferably forged integrally from the metal of the handle and brought together at each end of the elongated clearance space 4 of said element, and terminating in a rounded embracing jaw 5, 45 against which the pipe 6 is held by the jaw of the other element. Said other element comprises a shank or handle 7 having a threaded portion 8 engaging nut 9 which is pivotally mounted in sides 3 by means of oppositely 50 extending lugs or gudgeons 10, the nut and its bearing extension being preferably made integrally of one piece. At its other end threaded shank 7 is provided with a gripping jaw 11 having the teeth 12 at its outer end 55 adapted to grip pipe 6, as shown in Fig. 1 and

to coöperate with jaw 5 to tightly engage it for turning.

Nut 9 is, as will be understood, internally threaded for the reception of threaded portion 8 of shank 7, by which construction the 50 jaw 11 may be advanced or retracted towards or from jaw 5 for varying sizes of pipes, and when so adjusted and closed upon the pipe, the wrench will operate in a manner similar to the ordinary Stillson wrench. The 65 advantages of the construction result from the double-sided bearing for the pivoted nut 9 and in the threaded engagement therewith of shank 7 to provide for longitudinal adjustment, the pivotal mounting of the nut in the 70 manner shown giving great strength and durability, with resulting simplicity and cheapness of cost.

In assembling the construction as above described and as shown in the principal figures of the drawing, the sides 3 may be separated apart sufficiently far to permit of the insertion of bearing lugs 10 in their receiving openings, after which the sides 3 may be then closed inwardly and there held until set, 80 the operation being easily performed by previously heating the metal. The same result may be secured by casting the element 2 and its embracing arms 3 around the bars 10 of the nut and thereafter separating them 85 by rotation of the nut to accomplish the same pivotal mounting, and it will be understood that the invention is in no way limited to the method of manufacture.

In Fig. 4 I have shown a further modified construction wherein the nut 9 is mounted between sides 3 by means of independent inwardly extending bearing points 10', forming the inner terminals of screws as shown, or which may be riveted or secured in the sides 95 in any other suitable manner. With either construction the pivotal mounting of the nut 9 is accomplished whereby to permit of the opening and closing of the jaws and the longitudinal adjustment of the threaded stem 7 in 100 the same manner described.

I am aware that prior to my invention devices have been patented having for one of their objects longitudinal adjustment of one of the gripping elements, and am familiar with the patent of Stouffer No. 182492, dated September 19, 1876, wherein the jaw 13 is provided with threads at one side and is flattened at the other. Such construction however necessitates the turning of the jaw at 110

right angles to the main shank *a* for the purpose of making each adjustment by sliding motion, and the bearing plug *c* therein is mounted in its peculiar one-sided bearing. I do not broadly claim such construction, but

What I do claim and desire to secure by Letters Patent is:—

1. A pipe wrench consisting of a main bifurcated shank having a gripping jaw and a handle, an internally threaded nut having oppositely located bearing lugs pivotally mounted in and between the bifurcated sides, and a threaded shank engaging said nut and provided with a gripping jaw and a handle portion, substantially as set forth.

2. In a pipe wrench, the combination of a shank having divided sides with an intervening clearance opening, a terminal gripping jaw, and an oppositely extending handle; an internally threaded nut within said clearance opening having oppositely extending bearing lugs pivotally mounted in said sides; and a threaded shank engaging said nut and provided with a gripping jaw at one end arranged for coöperation with said first-named jaw, and an operating handle at the other end, substantially as set forth.

3. In a pipe wrench, the combination of a main shank having integrally separated sides and an intervening clearance opening, a terminal gripping jaw, and an oppositely extending handle; a nut mounted in said clearance opening provided with oppositely extending bearing lugs pivotally engaging said sides; and a threaded shank engaging said nut and provided with a toothed gripping jaw at one end and an operating handle at the other end, substantially as set forth.

4. In a pipe wrench, the combination with a main shank having a gripping terminal and a handle, a swiveled nut, and a threaded shank mounted therein having a gripping terminal and a handle; of pivoting bearings extending through the separated sides of the first-named shank and extending into said nut at opposite sides, substantially as set forth.

In testimony whereof I affix my signature in presence of two witnesses.

JABEZ COOPER.
